21

Nathaniel & Pearson Crosby of Pomfret New York
Letters Patent,

thickheaded referred to in these Letters Patent and making part
of the same containing a description in the words of the said
Nathaniel Crosby and Pearson Crosby themselves of their
improvement in the construction of Saw Mills.

To all to whom these presents shall come Be it known
that the Nathaniel Crosby and Pearson Crosby of Pom-
fret in the County of Chautauqua and in the state of New
York have invented constructed and applied to use a new
and useful improvement in the construction of Saw Mills
and that the following is a full and exact description there-
of, that is, to day. The Invention and improvement claimed
by the subscribers, is a balance wheel or a segment of a wheel
or weight made of cast iron or some other suitable material
of sufficient weight, and attached to the crank shaft, or
water wheel of a common Saw Mill in such a manner as
nearly to counterbalance the crank, pitman saw gate and
other superincumbent weight and thereby overcome and
equalize the jerking and irregular motion of the crank.

This wheel may be overhanging on the outside of the plumb
block and so made as to form the crank, or it may be af-
fixed to the shaft on the inside of the plumb block, or if
a segment of a wheel or weight it may be attached to any part of
the shaft or water wheel opposite to the crank so that it may
by counterbalance the said crank, pitman, saw gate and other
weight as aforesaid - In testimony that the above is a true
specification of our said Invention and improvement as above
described we have hereunto set our hands the twelfth day
of March in the year eighteen hundred and thirty five

Witness, *John Mullett* *3*
